US0D1046905S

(12) **United States Design Patent** (10) Patent No.: **US D1,046,905 S**
Chuang et al. (45) Date of Patent: ** Oct. 15, 2024

(54) **DISPLAY SCREEN OR PORTION THEREOF WITH GRAPHICAL USER INTERFACE**

(71) Applicant: **Acer Incorporated**, New Taipei (TW)

(72) Inventors: **Ching-Yuan Chuang**, New Taipei (TW); **Zheng-Yan Lee**, New Taipei (TW); **Chung-Hsien Lee**, New Taipei (TW); **Hsiao-Wei Chi**, New Taipei (TW)

(73) Assignee: **Acer Incorporated**, New Taipei (TW)

(**) Term: **15 Years**

(21) Appl. No.: **29/863,740**

(22) Filed: **Dec. 22, 2022**

(51) LOC (14) Cl. **14-04**

(52) U.S. Cl.

USPC **D14/486**

(58) **Field of Classification Search**

(57) **CLAIM**

The ornamental design for a display screen or portion thereof with graphical user interface as shown and described.

DESCRIPTION

The FIGURE is a front view of a display screen or portion thereof with graphical user interface showing our new design.

The dot-dash broken lines illustrate a display screen or portion thereof and form no part of the claimed design. The even-dash broken lines illustrate portions of the graphical user interface that form no part of the claimed design.

1 Claim, 1 Drawing Sheet
